UNITED STATES PATENT OFFICE

101,548

DESIGN FOR A TUB FOR A DOMESTIC WASHING MACHINE

Charles E. Morgenstern, Binghamton, N. Y., as-
signor to Nineteen Hundred Corporation, Bing-
hamton, N. Y., a corporation of New York

Application June 15, 1934, Serial No. 52,191

Term of patent 14 years

To all whom it may concern:

Be it known that I, Charles E. Morgenstern, a citizen of the United States, residing at Binghamton, in the county of Broome and State of New York, have invented a new, original, and ornamental Design for a Tub for a Domestic Washing Machine, of which the following is a specification, reference being had to the accompanying drawing forming a part thereof, in which:

Figure 1 is an elevation of a tub showing my new design, the tub being of substantially cylindrical form and the fluting shown being extended completely around the tub, and

Figure 2 is a horizontal section on an enlarged scale through the wall of the tub along the line 2—2 of Figure 1.

The characteristic features of the design are

the provision of an overturned flange at the top of the tub, an annular depression surrounding the tub adjacent the top but slightly below the lower edge of said flange, and the alternate arrangement of long and short groups of indentations spaced apart around the periphery of the tub, each group including three indentations, the central one of which is longer than the other two, which are of equal length, the longest indentation of the longer group being spaced substantially equidistantly from the bottom of said annular depression and the bottom of the tub.

I claim:

The ornamental design for a tub for a domestic washing machine, as shown and described.

CHARLES E. MORGENSTERN.
